United States Patent Office

Des. 178,982
Patented Oct. 23, 1956

178,982

TIRE

William F. Billingsley, Silver Lake, Ohio, assignor to The
B. F. Goodrich Company, New York, N. Y., a corpo-
ration of New York

Application June 24, 1955, Serial No. 36,662

Term of patent 14 years

(Cl. D90—20)

Fig. 1 is a perspective view of a tire showing my new design; it being understood that the design of the segment disclosed in full lines is repeated about the entire circum-ference of the tire.

Fig. 2 is an enlarged fragmentary view of the tread design that more clearly shows the nature of the kerfs in the tread elements.

I claim:

The ornamental design for a tire, as shown and de-scribed.
